UNITED STATES PATENT OFFICE.

WILLIAM H. STACY, OF WAYNESVILLE, OHIO.

COUNTER-BOX.

SPECIFICATION forming part of Letters Patent No. 364,316, dated June 7, 1887.

Application filed February 23, 1887. Serial No. 298,504. (No model.)

To all whom it may concern:

Be it known that I, WILLIAM H. STACY, a citizen of the United States, residing at Waynesville, in the county of Warren and State of Ohio, have invented a new and useful Improvement in Counter-Boxes, of which the following is a specification.

The ordinary method of handling nails and other small but heavy articles by the retail dealer is attended with considerable inconvenience and discomfort. Attempts have been made to provide counter-boxes which would readily discharge their contents, and thus obviate the necessity of removing such articles by hand from the kegs or other receptacles in which they are stored; but, owing to the cost of manufacture or other objection, none of these counter-boxes appears to have come into general use.

20 The object of my invention is to provide a simple and economical counter-box, from which the contents can be readily discharged without being handled by the dealer.

In the drawings, Figure 1 is a front view of 25 a series of my improved counter-boxes arranged under a counter or shelf; Fig. 2, a vertical section on the line 2 2 of Fig. 1, showing in dotted lines the box in position for discharging its contents.

30 A is a shelf or counter; *a a*, partitions under the counter, between which the counter-boxes may be placed; and *a' a'*, slats, herein-after called "rails," secured to the partitions, and serving as seats for the boxes when in position, and as rails upon which the boxes may be slid in and out of position. The partitions are illustrated as extending to the shelf, but will answer the purpose if extended sufficiently above the rails *a'* to serve as guides for the 40 boxes.

B is a counter-box having sides *c c*, with their lower extremities rounded in front, so as to form rockers *c' c'*, and front piece, *d*, inclining inward toward the bottom.

45 The box, having been filled, is placed upon the rails *a'* and slid into position. When any portion of the contents is to be removed, the box is tilted forward until the sloping front is sufficiently inclined to allow the nails or 50 other contents to drop out. The box is pro-

vided with a suitable handle, *e*, for convenience in tipping. In order to limit the space over which the discharge may take place, the front of the box is provided with converging stay-pieces *d' d'*. The rockers are provided at 55 suitable points with notches *c' c'*, adapted to take over the corners of the rails *a' a'*. Instead of a single notch adapted to engage with the corner of the rail, the rocker may be provided with one or more notches adapted to engage with corresponding projections upon the bearing-rail. These notches afford a temporary bearing for the box when tilted, and allow it to be tipped to any desired extent or shaken to facilitate the discharge of the contents without slipping from its bearings. When 60 the desired portion of the contents has been removed, the weight of the remaining portion tends to return it to its normal position by force of gravity. The box may be conveniently filled by removing it from the rails and placing the front against one of the partitions to prevent its tipping.

It is obvious that a curved rail may be substituted for a straight one, the lower end of 75 the box being correspondingly changed and the notch being placed in the curved surface.

I claim—

1. A tilting counter-box having the lower ends of its sides curved in front to form a rocking surface, in combination with rails adapted to serve as bearings for said box, said rocking surface being notched to engage said rails, substantially as and for the purpose specified.

2. In combination with bearing-rails, the 85 herein-described counter-box provided with a sloping front, and having the lower ends of its sides curved in front to form rocking surfaces, said rocking surfaces being notched to engage said rails, substantially as and for the 90 purpose specified.

3. A tilting counter-box having front piece, *d*, converging stay-pieces *d'*, and rockers *c'*, provided with notches *c' c'*, in combination with bearing-rails *a'*, substantially as and for the 95 purpose specified.

WILLIAM H. STACY.
